UNITED STATES PATENT OFFICE

121,390

DESIGN FOR A WATCH CLEANING MACHINE

Roy B. Keehnel, Independence, Mo.

Application April 8, 1940, Serial No. 91,538

Term of patent 7 years

To all whom it may concern:

Be it known that I, Roy B. Keehnel, a citizen of the United States, residing at Independence, in the county of Jackson and State of Missouri, has invented a new, original, and ornamental Design for a Watch Cleaning Machine, of which the following is a specification, reference being had to the accompanying drawing, forming part thereof.

In the drawing:

Fig. 1 is a perspective view of a watch cleaning machine showing my new design.

Fig. 2 is a front elevational view thereof.

Fig. 3 is a plan view thereof.

Fig. 4 is a side elevational view thereof.

I claim:

The ornamental design for a watch cleaning machine, as shown.

ROY B. KEEHNEL.
